(57) **CLAIM**

The ornamental design for a cleaning robot with protrusible side brush, as shown and described.

DESCRIPTION

Reproduction 1.1 is a front view of a cleaning robot with protrusible side brush, reproduction 1.2 is a back view thereof, reproduction 1.4 is a left view thereof, reproduction 1.5 is a right view thereof, reproduction 1.6 is a top view thereof, reproduction 1.7 is a bottom view thereof, reproductions 1.8 and 1.10 are two perspective views thereof, reproductions 1.3, 1.9 and 1.11 are enlarged detail views designated as A in 1.2, B in 1.8 and C in 1.10, respectively. The broken lines in the reproductions depict the portions of the cleaning robot with protrusible side brush that form no part of the claimed design.

1 Claim, 9 Drawing Sheets
